UNITED STATES PATENT OFFICE.

ROYAL A. HAWLEY, OF GRAHAM, TEXAS, ASSIGNOR OF ONE-THIRD TO J. DRIVER AND ONE-THIRD TO JOHN RUBENKOENIG, BOTH OF GRAHAM, TEXAS.

ROAD-GRADER.

1,213,869.

Specification of Letters Patent. Patented Jan. 30, 1917.

Application filed April 19, 1915. Serial No. 22,832.

To all whom it may concern:

Be it known that I, ROYAL A. HAWLEY, a citizen of the United States, residing at Graham, in the county of Young and State 5 of Texas, have invented certain new and useful Improvements in Road-Graders, of which the following is a specification.

My invention has relation to an improvement in road graders or scrapers and in 10 such connection it relates more particularly to the arrangement and construction of the support for the scraping blade, whereby said blade may be adjusted to any required angle in planes at right angles to each 15 other.

In road graders, as heretofore constructed, it was impossible to adjust the blade to perform all of the operations necessary and for this reason a series of machines was required to properly level, ditch 20 and bank the road. The ordinary scraper for instance was capable of cutting or scraping off more or less of the surface of the road in a flat plane and its blade was in 25 some instances laterally as well as vertically adjustable. Again in forming the ditch or trench at the sides of the road a plow was the usual instrumentality employed and in banking up the road still another arrangement of scraper was used to accomplish this 30 result.

In my present improved road grader or scraper, the blade is so supported and its bearings or supports are such that the machine 35 may be readily and quickly adapted to perform any and all of the operations necessary in road grading. My machine will scrape or level the road and it will bank the road and dig the ditches without removing 40 the blade from the machine since the support for the blade is provided with the usual vertical and lateral adjustment and is also adjustable angularly in a plane vertically of the machine as well as angularly in a 45 plane longitudinally thereof.

In carrying out my invention, the frame or body which connects the rear and front axles of the machine together is supported by the rear axle so as to have a vertical 50 and a lateral adjustment with respect to said axle and the rear of said frame is provided with a ring supported in a circular vertically disposed bearing and with means for swinging the frame completely around 55 in said bearing. The frame also carries

between its ends a circular bearing supporting a ring carrying the scraper blade and said ring is provided with means whereby the blade may be completely revolved in said bearing in a plane parallel with the 60 frame.

My invention broadly considered has for its principal object the provision of means for adjusting the blade in circular planes, one revolving about the longitudinal axis 65 of the machine and the other revolving about the vertical axis of the frame.

Subsidiary objects of my invention are to provide means for properly securing the various adjustments of the blade in circular 70 planes and of the frame in vertical and lateral straight planes.

The nature and scope of my invention will be more fully understood from the following description taken in connection with the 75 accompanying drawings, forming part hereof, in which,

Figure 1, is a side elevational view of a road grader embodying main features of my invention. Fig. 2, is a top or plan view 80 thereof, and Fig. 3, is a longitudinal sectional view taken on line *a*, *a* of Fig. 1.

Referring to the drawings, 1 represents the front and 2 the rear axle of the machine. These axles 1 and 2 form the support for 85 the body of the machine, said body comprising the two side rails 3 converging toward the front axle 1, a front bearing 4 turning on a pin or shaft 5 carried by axle 1 and a rear ring-shaped, vertically disposed, 90 frame 6 turning on an annular bearing 7, supported by the rear axle 2.

The annular bearing 7 is carried by a box-like frame work arranged to shift laterally along the rear axle 2. The axle 2 for this 95 purpose is formed preferably square in cross section and is hollow and provided with a top and bottom slot 8. In the hollow shaft or axle 2 are adapted to slide the block or blocks 9 traversed by screw threaded shafts 100, 10. The annular bearing 7, is carried by a plate 11 of rectangular shape, and the plate 11 is supported by the end yokes 12. The yokes 12 are loosely traversed by the shafts 10 and when shafts 10 are turned in either 105 direction in the blocks 9 the yokes 12 and plate 11 with the bearing 7 are elevated or depressed vertically with respect to rear axle 2. To secure this movement to shafts 10, each shaft is provided at its top with a 110

miter gear 13 meshing with similar gears 14 carried by horizontally arranged shaft 15. The shaft 15 turns in bearings 16 formed on the top of plate 11 and is operated by hand wheel 17 at one side of the machine.

The plate 11 and auxiliaries are also adapted to be shifted laterally along the hollow shaft or axle 2. The preferred means for accomplishing this shifting and the resultant horizontal or sidewise adjustment to the circular bearing 7 is illustrated in the drawings and is as follows:—The two yokes 12 carrying the plate 11 are each provided with a bracket arm 16^a in which the yokes may slide vertically and each arm 16^a at its free end is in screw threaded engagement as at 17^a with a horizontally arranged threaded shaft 18 turning in bearings 19 supported by the rear axle 2 at or near the extremities of said axle. A ratchet 20 and lever 21 serve to operate the shaft 18 to thereby cause the yokes 12, plate 11, vertical shafts 10 and blocks 9 to slide horizontally on the rear axle, the blocks 9 constituting the bearings within the hollow axle 2 for the entire structure.

To secure rotary movement of the ring shaped frame 6 and to thereby turn the body of the grader about the longitudinal axis 30 of the machine, there is formed on the periphery of said frame 6, a series of gear teeth 22 meshing with a cog wheel 23 carried by a short shaft 24 traversing and supported to turn in plate 11 and its necessary parts. A hand wheel 25 on shaft 24 gives required control of the movement to said shaft.

As a preferred means of properly supporting the frame 6 upon bearing 7, the bearing has a forwardly and upwardly projecting flange 7^a upon its periphery and behind this flange 7^a the frame 6 is arranged to revolve. The rear of bearing 7 is secured to plate 11 by means of bolts or screws 7^b to thereby lock the frame 6 between the plate 11 and flange 7^a. The periphery of bearing 7, the inner edge of flange 7^a and the face of plate 11 thus constitute the bearings for guiding the frame 6 in its circular or rotary movement. To strengthen the body of the vehicle at the rear end, straps 26 are extended from the frame 6 to the side rails 3.

Intermediate of their ends the side rails 55 3 support an annulus or circular plate 27 constituting a bearing block of preferred tubular or cylindrical form having at its lower periphery a flange 28. The flange 28 forms a portion of the bearing and also a support for a ring 29 having its upper periphery provided with gear teeth 30. The ring 29 constitutes the support for the grading or scraping blade 31 of the machine, said blade 31 being united preferably to the under face of ring 29 by means of straps 32.

The tubular bearing block 27 is secured to the side rails 3 by means of the curved straps 33 and 34. To operate the crown gear ring 29 a longitudinally arranged shaft 35 having a bearing in the strap 33 and a bearing 36 within the frame 6 is provided, at one end, with a miter gear 37 meshing with the crown gear of ring 29 and at the other end with a hand wheel 38. The forward end of the body of the machine is engaged with the front axle 1 by a pivotal connection 5 of any preferred construction which will permit the body to revolve on its connection 5.

From the foregoing description it will be understood that the blade 31 is provided with a universal adjustment in the machine. Thus the body, carrying blade 31, is adjustable laterally and vertically in straight planes with the blade projecting in a vertical plane from the body or with the blade projecting in circular planes when the body is turned in its vertical rotary bearing 7 at the rear axle, or with the blade projecting at varying angles to the longitudinal axis of the machine when its supporting ring 29 is turned in the body. Any portion of the body of the blade 31 may be presented to the ground, a corner (rear or front) only may be operatively employed; all or a portion of its lower edge may be presented to the surface and the angle which this edge makes with the road may vary from zero to 90 degrees or beyond. For ditch digging or for embankment, for plane grading or in fact for any required manipulation or operation there is in the machine the means for the necessary adjustment of the blade.

Having thus described the nature and objects of my invention, what I claim as new and desire to secure by Letters Patent, is,—

1. In a road grader, a frame connecting the front and rear axles of the machine, an annular bearing supported by the rear axle, a ring shaped vertically disposed frame forming the rear end of the machine frame and supported to turn on the said annular bearing, and a means supported by the rear axle and arranged to turn the ring shaped frame on said annular bearing.

2. In a road grader, a frame connecting the front and rear axles of the machine, an annular bearing supported by the rear axle, a ring shaped vertically disposed frame forming the rear end of the machine frame and supported to turn on the said annular bearing, and a means supported by the rear axle and arranged to turn the ring shaped frame on said annular bearing, combined with a scraper blade supported by the machine frame and arranged to revolve therein, a shaft traversing the annular bearing and arranged to turn the scraper blade and a manual means for turning said shaft, said manual means arranged within the annular bearing.

3. In a road grader, a frame connecting the front and rear axles of the machine, an annular bearing supported by the rear axle, a ring shaped vertically disposed frame forming the rear end of the machine frame and supported to turn on the said annular bearing, and a means supported by the rear axle and arranged to turn the ring shaped frame on said annular bearing, combined 10 with means for raising and lowering said annular bearing, the ring shaped frame and the means for turning said ring shaped frame, said raising and lowering means supported by the rear axle.
- 15 4. In a road grader, a frame connecting the front and rear axles of the machine, an annular bearing supported by the rear axle, a ring shaped vertically disposed frame forming the rear end of the machine frame 20 and supported to turn on the said annular bearing, and a means supported by the rear axle and arranged to turn the ring shaped frame on said annular bearing, combined 25 with means for shifting the annular bearing and ring shaped frame laterally of the rear axle, said shifting means supported by said axle.
5. In a road grader, a rear axle, a box like frame work arranged to shift laterally along the axle, an annular bearing supported 30 by said frame work, a frame having a ring shaped rear end supported to turn on the annular bearing, and a scraper carried by said frame, combined with means traversing the box like frame work and supported therein, said means arranged to turn said ring shaped rear end of said scraper-frame on said annular bearing.
6. In a road grader, a rear axle, a box like frame work mounted to shift laterally upon 40 the axle, an annular bearing carried by the frame work, and a scraper-frame supported to turn at one end on said bearing, combined with means traversing the box like frame work and axle and arranged to raise 45 and lower the frame work on said axle.

In testimony whereof I have signed my name to this specification.

ROYAL A. HAWLEY.
